UNITED STATES PATENT OFFICE.

CHARLES F. SMITH, OF NEW BRITAIN, CONNECTICUT, ASSIGNOR TO THE LANDERS, FRARY & CLARK, OF SAME PLACE.

DESIGN FOR A KNIFE.

SPECIFICATION forming part of Design No. 22,700, dated August 15, 1893.

Application filed July 1, 1893. Serial No. 479,392. Term of patent 7 years.

To all whom it may concern:

Be it known that I, CHARLES F. SMITH, a citizen of the United States, residing at New Britain, in the county of Hartford and State 5 of Connecticut, have invented and produced a new and original Design for a Knife, of which the following is a specification, reference being had to the accompanying drawings, forming part thereof, in which—

10 Figure 1 is a side elevation of a knife showing my design. Fig. 2 is an enlarged side elevation of the handle and ferrule portion of the same, and Fig. 3 is a plan view.

A designates the blade, B the handle and C the ferrule of my knife, the contour in side view being fully shown in Figs. 1 and 2, in which it will be seen that the blade is convex at its back and concave at its edge at the portion nearest the handle, while the edges toward the tip are curved in the reverse direction and meet in a point which projects obliquely upward. The handle B is also curved downwardly toward the butt as shown in side view while in plan view it is straight, although

tapering. An ornamental band 4 is on the 25 handle portion near the ferrule portion as shown. The ferrule portion consists of rounded and flat bands, the broadest one of which is an ornamental band 5 consisting of scroll figures on a roughened ground as shown, while 30 the bands 6 are fluted. It will be noticed that the design for the handle, especially in side view, is in harmony with the design for the blade, but the handle and ferrule of the design shown 35 may be used upon blades of other designs if desired.

What I claim is—

1. The design for a knife substantially as herein shown and described.
2. In a design for a knife the design for the handle and ferrule portion, substantially as herein shown and described.

CHARLES F. SMITH.
